DESIGN FOR A GLIDER

William I. Smith, Goshen, Ind., assignor to The
Hettick Manufacturing Company, Toledo,
Ohio, a corporation of Ohio

Application February 6, 1943, Serial No. 109,479

Term of patent 14 years

To all whom it may concern:

Be it known that I, William I. Smith, a citizen
of the United States and a resident of Goshen,
Elkhart County, Indiana, have invented a new,
original, and ornamental Design for a Glider, of
which the following is a specification, reference
being had to the accompanying drawings, forming
a part thereof.

In the drawings:

Figure 1 is a front perspective view of the glider,
showing my new design; and

Figure 2 is a rear perspective view of the glider
shown in Figure 1.

I claim:

The ornamental design for a glider, as shown.
WILLIAM I. SMITH.
